UNITED STATES PATENT OFFICE.

ELLSWORTH NELSON LUBURG, OF ARLINGTON, MARYLAND.

SLACK-ADJUSTER.

1,162,180.

Specification of Letters Patent. Patented Nov. 30, 1915.

Application filed March 6, 1913. Serial No. 752,414.

To all whom it may concern:

Be it known that I, ELLSWORTH NELSON LUBURG, a citizen of the United States, residing at Arlington, in the county of Baltimore and State of Maryland, have invented a new and useful Slack-Adjuster, of which the following is a specification.

My invention relates to improvements in slack adjusters especially in connection with the braking and equalizing mechanism of automobiles; and the object of my improvement is the providing of automatic means of taking up the slack to maintain a fixed amount of movement between the fully open position and the position when the brake is applied.

In a co-pending application Serial No. 682,910, filed March 11, 1912, I have illustrated, described and claimed a brake adjusting device similar in general mode of operation to that hereinafter described.

The herein described invention relates more particularly to a device combining the general principles of operation of that of the co-pending application with additional features of locking and releasing mechanisms.

A further object of my invention is to provide a means for preventing false adjustments, that is, causing the adjusting devices to operate improperly as might be the case should the brakes become jammed due to an accumulation of dirt or foreign substances.

35 A further object of my invention is the providing of means of preventing the taking up of slack from accidental means such as inadvertently tampering with the take up mechanism or other causes accidental or 40 otherwise, except through the systematic taking up through its own mechanism.

A further object of my invention is the providing of a definite means of holding or maintaining the brake-rod at a required 45 length and outside means of varying said positive means operated by said brake rod.

A further object of my invention is the providing of adjustable means of regulating the length of the brake rod by means of 50 stops on an independent rod operating mechanism adjusting the brake rod.

A further object of my invention is the providing of a machine of extreme simplicity and ease of adjustment and capable

of high speed in accomplishing the above 55 desired results.

With the foregoing and other objects in view my invention consists of the novel construction, combination and arrangement of parts as hereinafter specifically described 60 and illustrated in the accompanying drawings wherein is shown the preferred embodiment of the invention, but it is to be understood that changes, variations and modifications can be resorted to which come 65 within the scope of the claims hereunto appended.

In the drawings of the herein described embodiment of my invention, Figure 1 shows a view partly in section of my improved 70 slack adjuster. Fig. 2 shows a view of my improved slack adjuster as applied to an automobile brake. Fig. 3 is a view of the gear and pinion with the casing separated at the joint "CD". Fig. 4 is an enlarged view 75 taken through "AB" of Fig. 1 of the locking device. Fig. 5 is a sectional view taken through "E" of Fig. 1 and Fig. 6 is a sectional view taken through "G" of Fig. 3.

Similar numerals refer to similar parts 80 throughout the several views.

1 is a brake band which is secured to brake lever 2 in the usual way.

3 and 4 are the ends of the brake rod which are secured in the take up mechanism 85 as described later.

5 is the brake handle operating end 4 of the brake rod.

6 is a part of the fixed frame of the automobile and to which is secured guide 7 through which guide 7 operates operative rack rod 8 and on which rack rod 8 are secured stops 9 and 10. Between stops 9 and 10 on rack rod 8 is a sleeve 33 which is used for the purpose of protecting the adjusting 95 thread on rack rod 8 and give a smooth rod to operate through guide 7. On the other end of the operative rack rod 8 from that working through guide 7 is rack 11 which works inside of casing 12; the face of said 100

rack being flat, the rod being cut away prior to the forming of the teeth thereon as shown at 13, which construction prevents the rack from turning over when in use.

Rack 11 drives rack pinion 16 which pinion is secured to operative shaft 17 by being milled thereon or other convenient way. On operative shaft 17 is secured ratchet wheel

18, which in the drawing is integral with said shaft 17. Ratchet wheel 18 engages with and drives gear 19 by means of teeth on the face of said gear 19 thereby forming a face ratchet. Gear 19 is loosely mounted on shaft 17 and is maintained in mesh with ratchet wheel 18 by means of spring 20 which operates in pockets in gear 19.

10 Gear 19 drives pinion 21 which pinion 21 is secured to shaft 22 and on which shaft 22 is secured bevel gear 23 which bevel gear drives bevel pinion 24. Shaft 16 at one end is journaled into casing 14, which casing is screwed into and thus forms a flexible joint 15 with casing 15, and at the other end said shaft is journaled into washer 34 which washer 34 fits into a counterbore in casing 15, the shelf of which counterbore is shown at 35 in Fig. 3. Shaft 22 at one end is journaled into casing 15 and at the other end is journaled into casing 29. On the rear of bevel gear 23 are ratchet teeth 25 which are engaged by pin 26 which pin is held in place by spring 27.

25 Brake rod end 3 is secured in casing 28 by means of a male and female plug 36, the object of which plug is to facilitate the removal of brake rod 3 for repairs to the same without removing case 28, the said plug being secured in casing 28 and rod 3 screwed in said plug. Brake rod end 4 works freely through casing 29 and works through bevel pinion nut 24, which nut is formed integral with or secured to bevel 30 pinion 24, the whole carrying one number designation. At the outer end of casing 29 is stuffing gland 37 which secures packing 46 around brake rod 4 to protect the working parts of the same from dirt.

40 30 is a locking sleeve in which casing 12 operates at one end and the other end is secured to rack rod 8.

31 is a felt washer secured in the end of locking sleeve 30 by means of a spring retaining wire or washer 32.

41 is a locking block secured in projections of locking sleeve 30.

42 is the ball cradle in which are balls 43 which balls are separated by means of spring 44 and are kept engaged between the inclined surfaces 45 of locking block 41 and casing 12. Ball cradle 42 is secured to rod 46 and is operated thereby. Rod 46 works through guide 47 which is secured to locking sleeve 30 and formed integral therewith.

48 is a guide secured to rack rod 8 by means of stop 10 and through which rod 46 works, thereby maintaining rack rod 8 and locking sleeve 30 in proper rotative position.

60 On rod 46 are stops 49 and 50 which are adjustable thereon and on which stops are points or projections 51, the object of said projections being to have a more intimate and accurate contact of the same with guide

7 and stops 9 and 10 at the limits of movement of the combination. Stops 49 and 50 are adjusted on rod 46 sufficiently near stops 9 and 10 to release the ball in the brake when the two stops come together. Bevel pinion nut 24 is mounted in sleeve 28 by ball bearings.

The rod 4, for convenience, has an indicator groove 52 formed thereon, which serves the double purpose of carrying the lubricant through the tubular casing 29 and also serves to indicate when said rod 4 has been screwed into the rotary nut 24 a proper distance.

10 The stops 9 and 10, in practice, serve to move the rack bar 8 as they come into engagement with the stops 49, 50 after said stops 49, 50 impinge upon the guide member 7. The drawings do not illustrate the stops 49, 50 in proper relative position with reference to the stop members 9 and 10, and the ball-cradle, but it is to be understood that when adjusted, in practice, either of the stops 50, 51 impinge against the guide member 7 and move the ball-cradle to release the bar 8 for a longitudinal movement with reference to the casing 12 and the main strain for moving the rack bar 8 is taken up by either of the stops 9 or 10. The parts are presumed to be adjusted in proper proximity to each other to effect these results. In the showing of the drawings, however, and for the purposes of clearance, they are somewhat separated.

100 The operation of my invention is as follows: My slack adjuster being installed in the brake rod between the handle and brake or at any convenient place, guide 7 is secured to the frame or some convenient part of the automobile in such a position as to permit of the proper alignment of rack rod 8 operating therein. The stops 9 and 10 are properly adjusted on the operating rod 8 to permit a full movement of the handle 5 from a wide open position of the brake to a full closed position thereof. When properly adjusted under these conditions, the stops 50, 49 should barely impinge upon the guide member 7. If, for any reason due to wear or other causes, the brake rod extends sufficiently to permit the lever 2 to move still farther forward, as in the case of wear upon the brakes, the stop 49 will impinge against the guide 7, moving the ball cradle and unlocking the rod 8 with reference to the sleeve 12. Thereupon, the stop 10 will abut against the stop 49 and the rack bar 8 will be moved to rotate the pinion 16, ratchet wheel 18, said ratchet slipping over the teeth of the gear 19 without transmitting motion through the gear train. Upon releasing handle 5 and bringing the brake rods back to initial position or wide open, before that position is reached stop 50 engages with guide 7 and stop 9 engages stop 50, thus

85

holding operative rack rod 8, thereby turning rack pinion 16, operating shaft 17, ratchet wheel 18, gear 19 by means of engaging the teeth thereon, pinion 21, pinion 5 shaft 22, bevel gear 23 and bevel pinion nut 24, screwing the same on to end 4, the threaded end of the brake rods thus shortening the same until the handle goes back to initial position, the gearing and pitch of 10 screws being such that an equal longitudinal movement of rack rod 8 causes an equal longitudinal movement of the brake rod in taking up. The above feature, viz. the equal movement of the brake rod longitudinal to 15 the longitudinal movement of the rack rod is essential to make an exact adjustment in a single backward stroke if used as shown.

Concerning the locking mechanism to prevent a false movement of rack rod 8; normally 20 rack rod 8 by means of locking block 41 and the balls 43 being forced by spring 44 on to the reverse inclined surfaces 45 and against casing 12, is securely locked to said casing 12, thus preventing any relative end- 25 wise movement.

Upon reaching a point near the limit of the stroke of the combined appliance on the brake rod rack rod 8 operating through guide 7, stops 49 and 50 engage with guide 30 7 first thereby operating ball cradle 42, releasing the ball at the end of the cradle, thus permitting a relative movement of the rack rod 8 and casing 12 when stops 9 or 10 engage with guide 7 through stops 49 35 or 50.

Guide 7 may be placed on the automobile or on an operating part so there may be a relative movement between it and operating rack rod 8.

Having thus described my invention what I claim and desire to secure by Letters Patent is—

1. In a slack adjuster, means for taking up the brake rod to an extent equal to that 45 traversed by the brake rod past its normal regulated movement for braking, consisting of a mechanism having a fixed movement with the brake rod and positive stop devices for preventing its movement during 50 the excess movement of the brake rod, thereby transmitting through the excess movement motion for taking up the brake rod as it is moved and a clutch device normally locking the mechanism and controlled and 55 released by the stop devices.

2. A slack adjuster consisting of operative means of varying the length of the brake rod in combination with means of locking said operative means until a predetermined point of the movement of said 60 brake rod is reached and at which point automatic means of unlocking said operative means consisting of a casing moving with said brake rod and stop relatively fixed as 65 to said brake rod and through which a mem-

ber of said operative means works between predetermined limits and means of locking said member to said casing until a predetermined limit is reached.

3. A locking device for a slack adjuster 70 consisting of a sleeve through which a member of said slack adjuster operates which sleeve works with said slack adjuster, an operative end on said member operating through a relatively fixed guide through 75 predetermined limits, means of locking said sleeve and said operative end and means of releasing said locking means by said fixed guide at a predetermined point.

4. In a slack adjuster, means of shortening the brake rod consisting of a mechanism held at a relatively fixed point and operating to shorten the said brake rod as the same is moved, means of permitting said mechanism to have a predetermined range of 85 movement relatively to said fixed point before operating upon said brake rod and means of locking said mechanism relative to said brake rod until a limit of said movement relative to said fixed point is reached. 90

5. In a slack adjuster, a casing in which a brake rod is secured and operated, means for drawing said brake rod into the casing, said means including a reciprocating member adapted to move with said brake rod 95 during the normal adjusted movements of said rod and adapted to be held against movement during the excess movement of the brake rod, means for transmitting movement from said member to the brake rod 100 during movement of the latter and means for locking and releasing the reciprocating member relatively to the brake rod until said brake rod moves abnormally.

6. In a slack adjuster, means for taking 105 up the brake rod to an extent equal to that traversed by the brake rod past its normal regulated movement for braking, consisting of a mechanism having a fixed movement with the brake rod and a relatively fixed 110 stop for preventing its movement during the excess movement of the brake rod, a clutch and adjustable stops controlling said clutch and co-operating with the relatively fixed stop member whereby the mechanism 115 is unlocked upon engagement of the adjustable stops and fixed stop when the brake rod moves abnormally, thereupon transmitting motion through the excess movement of the brake rod and mechanism for taking up 120 said brake rod as it is moved.

7. In a device of the character described, a casing in which a brake rod is secured and operated, means for drawing said brake rod into the casing, said means including a reciprocating rack member adapted to move with said brake rod during the normal adjusted movements of said rod, a telescopic casing about said reciprocating rack bar, a gear-train intermediate said rack bar and 130

brake rod, a relatively fixed stop through which said rack bar passes, a clutch device mounted in one section of the telescoping casing and having an operating rod, adjustable stop members mounted upon said rod and adapted to control the clutch member as they impinge against the fixed stop whereby the telescoping sections of the cas-

ing are locked and released and thereby lock and release the reciprocating rack member ¹⁹ upon abnormal movements of the brake rod.

ELLSWORTH NELSON LUBURG.
